UNITED STATES PATENT OFFICE

DESMOND R. LA PLACE, OF PITTSBURGH, PENNSYLVANIA

STAPLING MACHINE

Application filed December 13, 1927. Serial No. 239,681.

This invention relates to stapling machines and more particularly to such machines using staples connected together to form strips.

One of the primary objects of this invention is to produce a stapling machine in which the force required for driving and clinching the staples is obtained by a powerful spring, instead of striking a punch-plunger by hand. 10 as now done with machines generally found in the trade. Another object of this invention is to provide a machine in which the intensity of the stroke of the shearing and driving plunger may be adjusted to suit the nature and thickness of the material to be 15 stapled together. Still a further object of this invention is the provision of a stapling machine which may be operated with the least effort, either in horizontal or vertical position. Additional features and advantages of this invention will appear from the following description considered in connection with the accompanying drawings forming a part of this application.

25 In the drawings:

Fig. 1 is a side elevation of the stapling machine in its inoperative position, one half of the frame having been removed to show the inside mechanism.

30 Fig. 2 is a similar view to Fig. 1, but showing the machine in closed position, about to shear off and drive a staple.

Fig. 3 is a perspective view of a shock absorbing spring used in the machine.

35 Fig. 4 is a fragmentary perspective view showing the staple feeding mechanism of the machine.

Fig. 5 is a perspective view of one of two staple catch-fingers used in the machine.

40 The purpose of this application is to cover important improvements and additions made on another stapling machine forming the subject matter of a copending application filed by me on August the 12th, 1925, and bearing the Serial No. 49,714, which has matured into Patent No. 1,655,275 granted Jan. 3, 1928.

Reference being had to the drawings, my improved staple driving and clinching machine comprises the housing 1 formed of two

symmetrical halves 1^a and 1^b held together by means of a suitable number of screws 2 inserted in threaded apertures 2^a. Said housing-halves are thickened at the front end and are suitably apertured to provide room for 55 the plunger-punch 3 and the lever spring 4 by means of which the plunger-operating lever 5 is automatically returned to the lowered or inoperative position shown in Fig. 1.

The operating lever is rockably mounted 60 on a fulcrum pin 6 and comprises the upper arm 7 and the angularly disposed lower arm 8. Rockably mounted adjacent the bottom of the lower arm 8, on a fulcrum pin 9, is the pawl 10 which is preferably made of 65 a piece of material bent to engage both sides of said arm, and which possesses a pointed nose 11 and lobes 12 through which the fulcrum-pin passes. A coil-spring 13, partly inserted in an aperture 14 provided in the 70 lower arm, is used to push said nose normally outward in a position adapted to enable it to engage the shoulder 36 on the plunger-punch 3. On the lower arm is also provided a protuberance or teat 15 which serves as a 75 guide for the lower end of the lever spring 4.

The plunger-punch 3 comprises a cylindrical guide-member 16 and the reduced punch 17 of substantially cruciform cross-section consisting of the narrow ribs 18 and the larger 80 front and rear ribs 19 and 20 respectively. The rear rib 20 is partly cut away at the lower end to produce the cutting edge 21 whereby the individual staples 22 are sheared off the staple-strip 23. These ribs slide in suitably 85 shaped grooves provided in both halves of the housing and their purpose is to hold the cutting edge 21 in proper shearing position. The guide-member 16 slides in the cylindrical aperture 24 and has at the top a central bore 25 to receive the lower end of the power-spring 26, the upper end of which occupies an aperture 27 provided in the outwardly threaded shank 28 of the grip or operating knob 29, this shank engaging threads 30 cut in the enlarged top portion 31 of the aperture 24. Said portion 31 is of sufficient depth to 90 allow for an ample adjustment of the pressure of the power-spring on the plunger-punch. 95

The staple-strip 23 is inserted in the ma- 100

chine at the rear through an opening 32 and straddles the rectangular staple carrying bar 33 which is securely held between the housing halves, and flush with the bottom thereof by dowel-pins 34 and by one of the screws 2. The front end 35 of the carrying bar is suitably ground and hardened to produce a sharp cutting edge at the top.

The operation of the punch-plunger and of 10 the staple shifting mechanism is performed by means of the plunger operating lever 5 in the following manner: The rear end of the housing is pivoted by means of a pivot-pin 37 between two vertical and parallel posts 38 15 formed integrally with, or secured in any desired manner to the base 39. At its upper end the lever arm 7 is slotted to receive the upper eye 40 of the connecting link 41 which is held by the pin 42. The lower end of said 20 connecting link has also an eye 43 and is hingedly mounted between the posts 38 on a through-pin 44, set a suitable distance back of the pivot-pin 37. It will be readily seen from Figs. 1 and 2 that, because of the disposition of the pins 37 and 44, when a downward pull is exerted on the operating knob 29, the housing will rotate counterclockwise and the operating lever 5 will be rotated clockwise. The rotation of the latter will first 25 30 compress the lever-spring 4 and then cause the nose 11 of the pawl 10 to engage the shoulder 36 of the punch-plunger and force the latter up into the position shown in Fig. 2, the power-spring 26 being thereby also compressed. Just before the bottom of the housing comes in contact with the top of the anvil block 45, the nose 11 leaves the shoulder 36 thus enabling the power-spring to rapidly 35 40 force the plunger-punch down whereby the first staple overhanging the cutting edge of the staple carrying bar 33 is sheared off, driven through the materials to be bound together, and the legs of the staple folded over upon striking the inclined or rounded sides of the 45 shallow groove or depression 46 in the anvil block.

The automatic forward feeding of the staple strip is obtained by securing in the lever 5 a rigid push-pin 47 having a bent portion 50 48 which engages a few turns at the forward end of the feeder-spring 49 the rear end of which is connected to the staple pusher 50 by means of a hook 51 formed at the rear end thereof.

55 The staple pusher is made up of a substantially rigid piece of sheet metal having at the rear two parallel wings 52 and at the front two spaced and parallel fingers 53 which straddle the spine 54 of the staple-strip 23 60 and the function of which is to engage the open spaces 55 provided between the individual staples to push the strip forward, when the housing is pressed down. In each wing 52 there are two longitudinal slots 56 65 each being engaged by a pin 57 secured in

both halves of the housing in any desired manner. The length of the slots 56 is such that the pins 57 will limit the forward shifting of the staple-pusher to advance the strip but one staple at a time.

70 When the depressed housing is released, the lever-spring 4 expands into its normal position and turns the operating lever 5 counterclockwise whereby the housing is turned up into the inoperative position illustrated in Fig. 2. The rotation of the lever 5 causes the push-pin 47 to strike a stop 58 properly located on the pusher and the latter is pushed back, the fingers 53 gliding easily over the top of the staple strip. The 80 purpose of using two slots 56 and two pins 57 is to positively guide the pusher 50 and prevent any overturning thereof due to the tension in the feeder-spring 49.

85 When but a few staples are left in the strip, the pressure by the striking plunger-punch is liable to displace or overturn the strip sufficiently to affect the proper operation of the machines. To prevent any trouble on this score, I secure in one of the housing halves the holding-down spring 59 the lower end of which lies flat on the top of the staple strip and the upper part of which is guided in an oblique slot 60 cut in a pad 61 formed inside of the housing-half. As 90 shown in Fig. 4, the holding spring has also at the top an angularly disposed extension which rests on the top of said pad and which engages an aperture 62 drilled in the housing-half; thus, said spring is properly held 100 to allow a yielding movement of the lower part thereof.

95 The staple-strip is additionally guided and held against retrogression by means of the lateral resilient catch-fingers 63 provided at 105 both sides of the carrying-bar 33 and acting near the cutting-edge thereof. Each catch-finger comprises the horizontal resilient arm 64 and the downwardly directed vertical finger 65 in which is produced a struck-up lug 66 adapted to engage one of the open spaces 55 in the staple-strip, adjacent the front end thereof. The front edge of said finger is also bent at right angles to form a rib 67 which acts as a guide for the foremost staple and enables it to be sheared off and driven in straight by the plunger-punch. The catch-fingers are secured to their respective housing-halves by means of rivets 68 inserted in apertures 69 cut at the inner end 110 of the arm 64.

115 In line with the staple-strip and carrying-bar there is provided at the front of the housing a sight-hole 70 to enable the operator to see whether or not the stapling machine is loaded.

120 As an additional improvement I have introduced in my new machine a shock-absorber 71 for the plunger-punch. This shock absorber comes into action when the 130

plunger-punch approaches the end of its downward stroke. As shown in the present embodiment this shock-absorber has the shape of a hair pin, the parallel legs 72 the rear part of which are set in grooves 73 cast in each housing-half. These grooves flare out gradually toward the plunger to afford room for the up and down flexing of the forward portion of the shock-absorber. The latter fits about the reduced portion of the plunger-punch and is engaged by the shoulder 36 when the plunger is pressed down. The purpose of this shock-absorber is to absorb the excessive impact or momentum of the plunger-punch when the latter has about reached the end of its stroke and to prevent any marring or denting of the materials stapled together, in cases that the power-spring should have been compressed too much.

My stapling machine may be used on level surfaces, such as the top of a desk, and on inclined or vertical surfaces, such as a wall. For the latter purpose, the base 39 of the machine is provided with apertures 74 for receiving suitable holding-down screws; in addition there are also provided resilient pads 75 to protect the surface on which the machine is set against scratching.

From the above description, the operation of the stapling machine will be readily understood and may be described briefly as follows:—

To bind together a number of paper-sheets, for instance, the operator holds with one hand the sheets in proper position on the anvil 45 and with the other hand forces down the whole housing by pulling on the knob 29. This causes the operating lever 5 to raise the plunger-punch and compress the power-spring 26 until the point 11 of the pawl 10 looses its engagement with the shoulder 36 of the plunger-punch 3. The latter is then quickly forced down by the released power-spring to shear off the first staple, drive it through the sheets of paper and clinch the legs of the staple thereunder. By releasing the grip on the knob 29, the lever-spring 4 acts on the operating lever 5 whereby the whole housing is raised in the upward position shown in Fig. 1. On the next downward pull on the knob 29, the staple next to be used is first moved forward by the pusher 50 into shearing position shown in Fig. 2 as soon as the plunger-punch rises above the top of the staple-strip.

It will be understood, of course, that the arrangement I have herein shown is merely suggestive of many that might be adopted in carrying out my invention, and I do not wish to be limited to the construction illustrated otherwise than as specified in the appended claims.

Having fully described my invention, what

I claim as new and desire to secure by Letters Patent is:—

1. In a stapling-machine, a base, a housing rockably mounted thereon, a plunger-punch reciprocable in said housing, an operating-lever for said plunger pivotally mounted in the housing, means positioned in said lever for lifting and subsequently releasing the plunger, and connecting means between said lever and base whereby the plunger will be lifted and subsequently released by the downward rocking movement of the housing. 70

2. In a stapling-machine, a base, a housing rockably mounted thereon, a plunger-punch reciprocable in said housing, an operating-lever for said plunger pivotally mounted in the housing, means positioned in said lever for lifting and subsequently releasing the plunger, connecting means between said lever and base whereby the plunger will be lifted and subsequently released by the downward rocking movement of the housing, and means for returning said housing into raised position. 80

3. In a stapling-machine, a base, a housing rockably mounted thereon, a plunger-punch reciprocable in said housing, an operating-lever for said plunger pivotally mounted in the housing, means positioned in said lever for lifting and subsequently releasing the plunger, rigid connecting means between said lever and base whereby the plunger will be lifted and subsequently released by the downward rocking movement of the housing, and means for returning said housing 90 into raised position. 95

4. In a stapling-machine, a base, a housing rockably mounted thereon, a plunger-punch reciprocable in said housing, an operating-lever for said plunger pivotally mounted in the housing, means positioned in said lever for lifting and subsequently releasing the plunger, connecting means between said lever and base whereby the plunger will be lifted and subsequently released by the downward rocking movement of the housing, and spring means for returning said housing 105 into raised position. 110

5. In a stapling-machine, a base, a housing rockably mounted thereon, a plunger-punch reciprocable in said housing, an operating-lever for said plunger pivotally mounted in the housing, means positioned in said lever for lifting and subsequently releasing the plunger, rigid connecting means between said lever and base whereby the plunger will be lifted and subsequently released by the downward rocking movement of the housing, and spring means effective 115 on said operating lever for returning said housing into raised position. 120

6. In a stapling machine, a base; a housing rockably mounted thereon; a plunger punch reciprocable in said housing; an operating lever for said plunger pivotally mounted in 130

the housing, and connecting means between said lever and the base adapted to rotate the lever on the housing in opposite direction relative to the rocking movement of said housing.

5 7. In a stapling machine, a base; a housing rockably mounted thereon; a plunger-punch reciprocable in said housing; an operating lever for said plunger pivotally mounted in the housing; means for normally holding said lever out of engagement with the plunger, and connecting means between said lever and base whereby the plunger will be engaged and lifted by the downward rocking movement of the housing.

10 8. In a stapling machine, a base; a housing rockably mounted thereon; a plunger punch reciprocable in said housing; an operating lever for said plunger pivotally mounted in the housing; means for normally holding said lever out of engagement with the plunger; connecting means between said lever and the base whereby the plunger will be engaged and lifted by the downward rocking movement of the housing, and means for returning said housing into raised position.

15 9. In a stapling machine, a base; a housing rockably mounted thereon; a plunger punch reciprocable in said housing; an operating lever for said plunger pivotally mounted in the housing; connecting means between said lever and the base whereby the plunger will be engaged and lifted by the downward rocking movement of the housing, and unitary means for holding said lever out of engagement with the plunger and said housing into raised position.

20 10. In a stapling machine, a base; a housing rockably mounted thereon; a plunger punch reciprocable in said housing; an operating lever for said plunger pivotally mounted in the housing; connecting means between said lever and the base whereby the plunger will be engaged and lifted by the downward rocking movement of the housing, and unitary spring means for holding said lever normally out of engagement with the plunger and said housing into raised position.

25 11. In a stapling machine, a base; a housing rockably mounted thereon; a plunger punch reciprocable in said housing; an operating lever for said plunger pivotally mounted in the housing; connecting means between said lever and the base whereby the plunger will be engaged and lifted by the downward rocking movement of the housing, and a spring positioned in the housing and acting upon the lever to keep the same normally out of engagement with the plunger and to hold the housing into raised position.

In testimony whereof I affix my signature.
DESMOND R. LA PLACE.
